UNITED STATES PATENT OFFICE.

LUTHER C. BACHELDER, OF PORTLAND, OREGON, ASSIGNOR TO AMERICAN CAN COMPANY, OF NEW YORK, N. Y., A CORPORATION OF NEW JERSEY.

FINGER-GAUGE-TRUING DEVICE.

Application filed May 13, 1921. Serial No. 469,116.

This invention relates in general to slitting machines for cutting sheets of tin and the like, and has particular reference to the provision in such a machine of means for 5 squaring or aligning a sheet in parallel relationship with respect to the line of the cutters employed in said machine prior to the reaching of said cutters by any part of the sheet.

In operating machines of this character it has been found to require the services of skilled and experienced operators to so manipulate the tin sheets or blanks as to prevent spoilage or wastage of considerable portions 15 of them through inaccurate cutting. It is a principal object of my invention to provide means whereby inexperienced operators can slit the tin as accurately and with as little waste as could experienced operators under 20 the old methods.

A further object of the invention is the provision of truing means of simple construction, which are adapted to be readily positioned upon a machine of the character 25 described, and operable by the normal movement of the blanks towards the cutters.

A further and important object of the invention is the provision of truing means practically automatic in operation and 30 adapted to function regardless of the degree of skill exercised by operators.

Numerous other objects and advantages of the invention will be apparent as it is better understood from the following description, 35 which, taken in connection with the accompanying drawings, discloses a preferred embodiment thereof.

Referring to the drawings:

Fig. 1 is a side elevation in broken section 40 of the portion of a slitting machine upon which my invention is employed;

Fig. 2 is an inner elevational view of one of the end brackets;

Fig. 3 is an enlarged detail of the upper 45 end of the bracket shown in Fig. 2, certain parts being shown in section; and

Fig. 4 is an enlarged sectional elevation taken vertically through the truing device and a portion of the slitting machine.

In the manufacture of tin cans of the ordinary commercial types, referring particularly to the cutting of can body blanks, the body blanks are cut from large standard size sheets.

The exact number of blanks procured from

each standard sheet depends entirely on the size of the body blank required. When making the small one pound cans or similar sizes as many as ten or twelve or more body blanks may be procured from each stock sheet. When making cans of the gallon or ten pound size, only three or four body blanks may be obtained from each stock sheet. The stock sheets as procured from the tin plate mill are given nominal overall 60 dimensions, and the sheets are intended to be made approximately square. In quantity manufacture, however, the large stock sheets are all more or less out of square and on this account are ordered a little larger in overall 65 dimensions than is necessary to cut the required number of body blanks from each stock sheet, the excess metal being trimmed off as waste in the operation of cutting the stock sheets into can body blanks. 70

In cutting these stock sheets up into can body blanks it is necessary that each body blank is square or accurately rectangular and of fixed length and breadth dimensions.

In order to get a starting point for cutting accurately square and truly dimensioned can body blanks it is necessary to first trim two opposite edges of each stock sheet by passing them successively through a trimming slitter. During this trimming operation the stock sheet is also slit into two or more sheets, each having a width equal to can body blank length. 80

Exact gauging in this trimming operation is not necessary, it having been found sufficient to simply manually or automatically advance the sheet along a side gauge bar into the grip of the trimming and slitting cutters. This side gauge bar may be adjusted square with the cutters or slightly out of square as may be desired, for as soon as the stock sheet of tin is engaged by the cutters and feed rolls it is immediately advanced automatically through the machine and the two opposite edges trimmed in parallel relation and the sheet slit into as many smaller sheets as are desired. These trimmed sheets are now ready to pass through the regular body cutting slitter and be cut up into can body blanks. It will now be noted that the original stock sheet has two of its opposite edges trimmed parallel and has also been slit into two or more smaller sheets having two parallel edges, while the edges of the sheets that were at right angles to the di- 90 95 100 105 110

rection of travel through the machine are still untrimmed, irregular and out of square with the trimmed and slit edges of the multiple sheets cut from each stock sheet.

5 These sheets are now taken in packs to the slitters where can body blanks are cut. These packs are arranged in convenient position at the front or at either side of the slitter feed table for hand feeding, the position depending on the preference of the individual operators. The packs are so oriented that the individual sheets are advanced to the slitting cutters at right angles to their direction of travel through the before mentioned trimming slitters. This brings the parallel trued edges of each sheet into approximately parallel relation with the bank of slitting cutters. Now must come into play some means of bringing the front trued edge of 20 each sheet exactly parallel with the bank of slitting cutters so that the line of cuts dividing the sheet up into can body blanks are exactly at right angles to the previously trimmed edge of the sheet. This is absolutely necessary or true and square can body 25 blanks cannot be produced.

One method that has been in quite extensive use comprised a mechanically reciprocating feed slide moving toward and away from 30 the slitting cutters and having a moving gauge bar set in a position to parallelize the back edge of the sheet with the bank of cutters, the sheet being meantime held against this gauge bar by a back pull of the operator's hand lying on top of the sheet. This 35 gauge bar carried a small adjustable stop block against which the corner of an untrimmed edge of the sheet was stopped to give the sheet proper lateral adjustment so that each untrimmed edge would be trimmed 40 as the sheet was being cut into can body blanks. This method of feeding is only satisfactory in some respects and limits the speed of operation by causing the operator 45 to watch the movement of the feed slide, as it is only practical to place a sheet when the slide is on the back stroke, and the slide having positive, uninterrupted reciprocating motion the sheets have to be placed in quite 50 regular sequence or they will be advanced into the cutters before being properly placed against the moving feed bar, resulting in the entire sheet being cut up into out of square body blanks, all of which must be rejected as 55 waste. The number of can body blanks so spoiled in a day's run has sometimes been so great as to very materially increase the cost of the finished product and some better and more efficient means of gauging the sheets 60 has been much desired and my improved method described and illustrated herein quite successfully supplies this need.

Upon the drawings employed for the purpose of illustrating the invention, I have 65 shown in outline a part of a slitting ma-

chine, the reference numeral 11 indicating a shaft upon which cutter members 12 are mounted, these members being adapted to cooperate with the lower cutter members 13 similarly mounted upon a shaft 14.

70

Mounted on the cutter hubs adjacent the cutters 12 and 13 are feed rolls 12^A and 13^A the same as are in common and general use. These rolls have the function of gripping the sheet and drawing it through the slitting cutters 12 and 13.

75

The cutting operation performed by these members need not be particularly described, since it is not essential to an understanding of my invention. It need only be pointed out that the sheets or blanks of tin are advanced, usually by automatic means, upon a table 15 and passed between the rotating cutters. In order to effect accurate cutting it is manifestly necessary that the blanks be perfectly aligned when they are presented to the cutters, and this has been found to be very difficult and to require considerable skill to accomplish when the blanks are aligned by hand. For the purpose of obviating this difficulty, I provide finger gauges 16 disposed at intervals in the path of the advancing sheets, the exact number of these members being unimportant excepting that there must be at least two. The upper ends 17 of 80 the finger members 16 are turned to horizontal position and secured by means of screw threaded engagement as at 18 in hub members 19, which are feathered to a shaft or rod 21, and held rigidly in place by means of bolts 22 (Fig. 1). At each end of the machine and secured to the table 15 are brackets 23 and 24, held in place by means of bolts 25 and 26. These brackets have their upper 85 ends 27 turned forward and they terminate 90 in bearings 28 and 29 in which the rod 21 is loosely secured. Upon the rod 21 and near the bearing 29 is feathered a collar 30 having integral therewith a bored lug 31, said lug being so positioned as to extend back 95 toward the vertical portion of the bracket 24. Extending inwardly from the bracket is a projection or flange 32, positioned immediately above the inner part of the lug 31. Extending through an aperture 33 in the lug 100 115 31 is a bolt or pin 34, an inner threaded end 35 of which is engaged in the flange 32. Upon the bolt are collars 36 and 37, the one of which bears against the lug 31 and the other against a nut 38 on the outer end of 120 the bolt. Between these collars is a spring 39 adapted to press the lug upwardly and against the flange 32. A bolt 41 extends through the flange 32 and its lower end 42 provides a stop for the upwardly pressed lug 125 31. It will be noted that this arrangement limits turning of the rod 21 in clockwise direction (viewing Fig. 4), and in the other direction only against the pressure of the spring 39.

130

When a sheet of tin is advanced in irregular position its forward edge will contact with one of the fingers 16 and further movement will be restrained until the free or 5 lagging part of the sheet is advanced to contact with the other finger, thereby truing the sheet and aligning its edge in position parallel with the horizontal line of the cutters. Further pressure of the sheets against 10 the fingers 16 will cause them to advance and be lifted to the position indicated by dotted lines in Fig. 4, this being permitted by rotation of the rod 21 against the pressure of the spring. The fingers are so set 15 that when they have been pushed forward by the sheets to the clearance position, just referred to, they have a tendency to drag and upon the passing of the sheet from beneath them they are forced back to original position 20 by the tension of the spring 39.

This accurate gauging action is brought about in the following manner:

In addition to my improved gauging fingers the ordinary fixed gauge bar at one side 25 of the feed table is employed to properly locate the sheet laterally and bring it into exact position to have each untrimmed edge, trimmed as the sheet is slit into can body blanks.

30 In gauging and feeding sheets into the slitting cutters it is also very necessary that the gauging and aligning devices control the sheet until engaged, by the cutters and feed rolls, otherwise a previously, accurately 35 aligned and gauged sheet may be moved out of perfect adjustment after being released by the gauging devices and before being gripped by the cutters and feed rolls, when it will be slit out of square and thus spoiled. 40 I establish this desirable and necessary condition through the correct placement of the gauging fingers in relation to the slitting cutters and feed rolls.

45 By reference to Figure 4 it will be noted that the lower ends 43 of the fingers 16, rest in gauging position slightly in front of the vertical line through the cutters 12 and 13 and that the sheet is gauged and aligned by being held in contact with the gauge fingers 50 until the forward edge is engaged by the cutters and feed rolls, when it is immediately advanced automatically and the gauge fingers are given their final movement out of engagement with the front edge of the sheet 55 and into the position indicated by dotted lines, where it will be noted the gauging points are on the opposite side of the vertical line through the cutters. It is thus seen that the gauging and aligning of a sheet by my improved method is most accurately, 60 positively and rapidly accomplished and that a skilled operator is unnecessary.

65 The preliminary operation of gauging and aligning a sheet is practically accomplished without effort or attention from the opera-

tor. An operator lays the flat of his hand on the top sheet of a pack and quickly slides it onto the feed table up against the regular fixed side stop, an untrimmed edge being against this stop, and by a slight forward movement pushes the sheet against one or another of the resistant gauge fingers. The gauge fingers are usually set to engage the edge of the sheet near the ends so that the operator's hand rests on the sheet intermediate the gauge points, thus a triangle of two resistance points and one intermediate pressure point is formed. The corners of the triangle comprise the two gauge points and the operator's hand. When the sheet engages one or the other of the gauge finger points, the operator is pushing the sheet forward against the finger points which remain in their normal first gauging position through the tension of the spring 33 and 70 thus resist movement until sufficient pressure is applied by the operator, pushing the sheet, to overcome the resisting tension of the spring 33. In the meantime the constant push of the operator's hand will swing the sheet into engagement with both finger gauges, because there is less resistance met by the sheet when in contact with only one finger gauge so that it will naturally swing 75 into correct alignment against both the 80 gauge fingers before the operator can exert enough pressure to swing the gauges forward, as soon, however, as the sheet touches both gauge fingers the operator's push will move the sheet in a straight forward direction 85 swinging the gauge fingers out of its path while entering into engagement with the feed rolls and immediately be carried through the machine, in perfect alignment.

90 This method and action is entirely different from any heretofore used in this art and produces a result in accurate and rapid gauging and cutting not before accomplished. The speed with which can body blanks may 95 be accurately produced is only limited to the 100 rotative speed of the cutters and feed rolls, which control the time in which the sheets pass through the machine. With the operator's mind concentrated on only the one task of getting the sheets against the fixed side 105 gauge and pushing the sheet into the machine he can manipulate the sheets as rapidly 110 as they are carried through the machine.

115 It will be noted that the construction is or may be such that the tips 43 of the fingers cross the line of bite of the feeding rolls, so that the sheet is securely held by the latter at the time it is released by the fingers. That is to say, the sheet is seized while it is accurately gauged. After the sheet passes the 120 fingers swing back to meet and align the 125 subsequent sheet.

130 It is thought that the invention and many of its attendant advantages will be understood from the foregoing description, and

it will be apparent that various changes may be made in the form, construction and arrangement of the parts without departing from the spirit and scope of the invention or sacrificing all of its material advantages, the form hereinbefore described being merely a preferred embodiment thereof.

I claim:

1. The combination of sheet cutting means, 10 rolls for grasping and feeding sheets through said cutting means, and two gauges spaced apart from each other and arranged in the path of the sheet, in front of the same, and each offering resistance to the movement of the sheet and connected and movable together out of the way of the sheet to allow the same to pass when properly arranged for the cutting operation, the resistance of one of said gauges causing the sheet to turn until it also bears against the other gauge, whereupon the movement of the sheet moves both gauges simultaneously out of the way of the sheet.
2. The combination of sheet slitting rolls 25 having cutting edges and sheet feeding surfaces, and two gauges spaced apart from each other and arranged in the path of the

sheet in front of the same and each offering resistance to the movement of the sheet and connected and movable together out of the way of the sheet to allow the same to pass when properly arranged for the cutting operation, the resistance of one of said gauges causing the sheet to turn until it also bears against the other gauge, whereupon the movement of the sheet moves both gauges simultaneously out of the way of the sheet.

3. The combination of sheet cutting means, 30 rolls for grasping and feeding sheets through said cutting means, and two gauges spaced apart from each other and arranged in the path of the sheet in front of the same and substantially at the line where the sheet is grasped by the rolls and each offering resistance to the movement of the sheet and connected and movable together out of the way of the sheet to allow the same to pass when properly arranged for the cutting operation, the resistance of one of said gauges causing the sheet to turn until it also bears against 45 the other gauge, whereupon the movement of the sheet moves both gauges simultaneously out of the way of the sheet.

LUTHER C. BACHELDER.
